US0D1003446S

(12) **United States Design Patent** (10) Patent No.: **US D1,003,446 S**
(45) Date of Patent: ** Oct. 31, 2023

(54) **MECHANORECEPTION STIMULATION
WEIGHTED BATON**

(71) Applicant: **NABOSO TECHNOLOGY INC.**,
Chandler, AZ (US)

(72) Inventor: **Emily Splichal**, Chandler, AZ (US)

(73) Assignee: **NABOSO TECHNOLOGY INC.**,
Chandler, AZ (US)

(**) Term: **15 Years**

(21) Appl. No.: **29/823,643**

(22) Filed: **Jan. 19, 2022**

(51) LOC (14) Cl. **24-01**

(52) U.S. Cl.

USPC **D24/211**

(58) **Field of Classification Search**

USPC D24/127, 130, 133, 188, 200, 211, 212,
D24/213, 214, 215; D22/117; D21/672,
D21/725

CPC .. A61H 19/40; A61H 7/003; A61H 2205/021;
A61H 7/007; A61H 19/44

(57) **CLAIM**

The ornamental design for a mechanoreception stimulation weighted baton, as shown and described.

DESCRIPTION

FIG. 1 is a perspective view of a mechanoreception stimulation weighted baton showing my new design;

FIG. 2 is a front side elevation view;

FIG. 3 is a rear side elevation view;

FIG. 4 is a left side elevation view;

FIG. 5 is a right side elevation view;

FIG. 6 is a top side elevation view; and,

FIG. 7 is a bottom elevation view.
